UNITED STATES PATENT OFFICE.

BENNETT W. HAMMOND, OF OAKLAND, CALIFORNIA.

PULLEY-BLOCK.

No. 876,176.

Specification of Letters Patent.

Patented Jan. 7, 1908.

Application filed June 11, 1907. Serial No. 378,429.

To all whom it may concern:

Be it known that I, BENNETT W. HAMMOND, a citizen of the United States, residing at Oakland, in the county of Alameda and State of California, have invented new and useful Improvements in Pulley - Blocks, of which the following is a specification.

This invention relates to pulley blocks which can be made with a hook, shackle, or other means for holding the same.

The object of the invention is to provide a simple and effective article of this character which, in addition to the ordinary uses of this style of block, such as for hoisting and logging purposes, can also be used in water, mud, sand, or other foreign matter without injury to its bearings.

In the drawings accompanying and forming a part of this specification I show in detail one advantageous form of embodiment of the invention which, to enable those skilled in the art to practice the same, will be fully set forth in the following description, while the novelty of the invention will be included in the claims succeeding said description.

Referring to said drawings, Figure 1 is a cross-sectional view of a pulley block involving my invention, the hook which generally forms part of the same being in elevation.

Fig. 2 is a side elevation of the same with a portion of the block removed and in section. Fig. 3 is a cross-sectional view of a modified form of pulley block also embodying my invention.

Like characters refer to like parts throughout the several figures of the drawings.

The device includes in its make-up a pulley or sheave which may be of any desirable character, but which is ordinarily peripherally grooved or channeled to receive a wire rope, cable, or equivalent part. The pulley or sheave shown in the drawings is denoted by 2 and it is located between the companion plates or cheeks each denoted by 3, and which, although they may be of any desirable cross-sectional shape, are illustrated as being concavo-convex within their peripheries with the concave sides next the intervening pulley. The two plates are generally in disk-form.

I have shown as fitted closely against the outer faces of the two plates 3 and as extending radially thereof the two side straps 4, said straps and the plates being perforated 55 to receive the bearing pin 5 of the pulley or

sheave 2. The straps 4 extend outwardly beyond the margins of the plates 3 and at their outer ends they are shown as bridged by a bar 6, the bar being connected to the two straps in any desirable way. For example, 60 the outer ends of the straps may be bifurcated and the cross or bridging-bar 6 can fit between the branches of the bifurcation, while pins each denoted by 7 may be utilized for uniting the bar with the two straps. The 65 shank of a hook as 8 is represented as swiveled to said bar 6 between the two straps 4. The bearing pin 5 has between its ends an enlarged portion or hub as 9 on which the pulley 2 turns, although a bushing 10 is illustrated as interposed between the wall of the opening of the pulley and the outer surface of the enlargement or hub 9.

I prefer to locate between the two plates or cheeks 3 and the pulley 2 the plates 11 of 75 similar nature and which are furnished at their peripheries with inwardly - extending annular flanges 12. The two plates 11 with their annular or circular flanges 12 present what might be considered a packing box. 80 The inner edges of the flanges 12 are separated or spaced from the web of the pulley 2, as clearly shown in Fig. 1, so as to obviate friction between such parts at said place.

The opposite ends of the pin or shaft 5 are 85 represented as threaded to receive the nuts 13, which latter are adapted to fit against the outer faces of the two straps 4. When the nuts 13 are set up they press or clamp the straps 4, plates 3, and plates 11 solidly 90 against the shoulders at the ends of the hub 9. It will be understood that the reduced ends of the pin or shaft 5 extend through the two plates 11, and the fit is a tight one. It therefore follows that, when the two plates are in 95 abutment against the ends of said hub 9, there are provided water - tight joints between the opposite ends of said hub and the two plates 11.

The hub of the pulley 2 is shown as being 100 somewhat wider than the web thereof, and around this hub at opposite sides of the web I prefer to fit packing rings as 14. These rings are usually compressed, being brought to this condition when the two plates 11 constituting the packing box are put in place. Their outer faces bear against the inner faces of the two plates 11 and hold the latter from contact with the pulley, so that free rotation of the latter is possible. The packing rings 110

14 are, as will be seen, interposed between the pulley 2 or the hub thereof and the annular flanges 12, so as to prevent the entrance of water or other undesirable substance into the 5 interior of the pulley or toward the bearing part thereof.

I prefer to surround the circumferences of the two annular flanges 12 by packing rings as 15 arranged in pairs respectively at opposite 10 sides of the web of the pulley, said pairs of packing rings 15 being preferably held in position by endless coiled springs as 16. The springs, however, preferably do not bear directly upon the said outer packing rings 15, 15 but against divided metallic strips as 17 interposed between the respective springs 16 and pairs of rings 15. The ends of the two divided strips are shown as overlapped in Fig. 2. These bearing strips with the several 20 packing rings previously described prevent water and other foreign materials from entering the bearing surfaces of the pin 9 and pulley 2. I, therefore, effectually prevent entrance of such foreign matters to the working 25 or moving parts from all directions, which is an important consideration, particularly when the appliance is put to submarine use.

The web of the pulley is represented as 30 having cross-sectionally curved flanges 17^a, the presence of which produces channels at opposite sides of said web, and in these channels the outer pairs of packing rings 15, strips 17, and springs 16 are disposed, the 35 walls of the channels thus formed holding the several parts in place. The side plates or cheeks 3 are shown as being of greater diameter than the pulley 2, by virtue of which the cable or band around the pulley is prevented 40 from jumping from the peripheral groove or channel therein. It might be stated, although it is believed it will be clear upon an inspection of the drawings, that the outer pairs of packing rings 15 engage against the 45 outer faces of the pulley 2.

It will be evident from what has been previously set forth that I provide a pulley, a journal for the pulley, and means for preventing the entrance of water to the journal. 50 When I use the expression "water" I, of course, intend to include thereby other foreign substances such as mud or dirt. The means in question are of such character that water is prevented from entering the bearing 55 surfaces of the device axially and radially of the pulley. These results may, of course, be accomplished in a variety of ways within the spirit of my invention, although I have hereinbefore particularly indicated one mode of 60 procedure for obtaining the results named.

I will now set forth a modified form of the device which possesses all the advantages following the construction illustrated in Figs. 1 and 2.

65 Referring to Fig. 3, the pulley block repre-

sented thereby involves in its construction two side plates or members 3' connected together, for example, by screw-threaded joints with the pin or shaft 5', the plates or sides 3' being adapted to abut or substantially abut against the ends of the enlarged portion or hub 9' on said pin. The enlarged portion of the pin or shaft 5' is provided with a bushing 10' on which the pulley 2' turns. The ends of the hub of the pulley are contiguous to the inner faces of the side plates 3'. The end portions of said hub are surrounded by packing rings as 14'. The inner faces of these packing rings 14' abut against the side faces of the web of the pulley 2', while the 70 outer faces of said rings are contiguous to the inner faces of the plates 3'. I have shown on the inner faces of said side plates 3' annular shoulders or flanges as 12' which enclose respectively the two packing rings 14' 75 and which are in turn encircled by pairs of packing rings as 15' surrounded by springs as 16'. The two plates 3' are shown as bridged by a connecting bar 6' pivotally connected with the respective plates and to 80 which the shank of a hook as 8' is swiveled. The shaft or pin 5' may if desired be provided with a lubricating passage as 5^a, the outer end of which is closed by a removable screw-threaded plug as 5^b. 90

What I claim is:

1. A pulley, plates located at opposite sides of the pulley, a journal for the pulley, extending between said plates, said journal having shoulders against which said plates 10 abut, and inner and outer packing rings fitted against the pulley, at opposite sides thereof, the inner rings bearing against said plates.

2. A pulley, plates located at opposite 10 sides of the pulley, a journal for the pulley, extending between said plates, said journal having shoulders against which said plates abut, inner and outer packing rings fitted against the pulley at opposite sides thereof, 11 the inner rings, bearing against said plates, and spring means encircling the outer packing rings.

3. A pulley, a journal for the pulley, having shoulders, a packing box in sections at opposite sides of the pulley, means for clamping the sections of the packing box against said shoulders, packing means between the pulley and the packing box, and packing means surrounding the packing box. 11

4. A pulley, a journal for the pulley, a packing box associated with the pulley, a packing between the pulley and the packing box, a packing surrounding the packing box, and an annular spring for holding the latter 12 packing in place.

5. A pulley, a journal for the pulley, a packing box associated with the pulley, a packing between the pulley and the packing box, a packing surrounding the packing box, 13

an annular spring for holding the latter packing in place, and a strip between said latter packing and spring.

6. A pulley, a journal for the pulley, a packing box in sections located at opposite sides of and out of contact with the pulley, the sections having inturned flanges, packings at opposite sides of the web of the pulley and located between the hub thereof and said flanges, said journal being shouldered, means for clamping the sections of the packing box against the shouldered portion of the journal, and packing rings surrounding the flanges.

15. 7. A pulley, a journal for the pulley, a packing box in sections located at opposite sides of and out of contact with the pulley, the sections having inturned flanges, packings at opposite sides of the web of the pulley and located between the hub thereof and said flanges, said journal being shouldered, means for clamping the sections of the packing box against the shouldered portion of the journal, packing rings surrounding the flanges, 25 and annular springs surrounding the respective rings, the web of the pulley having channels to receive said springs.

8. A pulley, a pin having a shouldered por-

tion between its ends, on which said pulley turns, plates at opposite sides of said shouldered portion; and other plates against the first mentioned plates, the pin extending through the several plates, straps through which the pin extends, nuts fitted to said pin for joining the several plates together and 30 the inner ones against the ends of said shouldered portion, said inner plates having in-turned annular flanges, and packings between said in-turned annular flanges and the pulley. 40

9. A pulley, a pin for the pulley, having shoulders, side plates fitted to the pin and abutting against the shoulders, a pulley rotative around the journal, packings surrounding the pulley, the side plates being flanged 45 to inclose said packings, other packings surrounding the flanges of said plates, and springs for holding the last-mentioned packings in place.

In testimony whereof I have hereunto set 50 my hand in presence of two subscribing witnesses.

BENNETT W. HAMMOND.
